UNITED STATES PATENT OFFICE.

JOHN J. HOFFMAN, OF NEW KENSINGTON, PENNSYLVANIA, ASSIGNOR, BY MESNE ASSIGNMENTS, TO P. H. MURPHY COMPANY, OF PAENASSUS, PENNSYLVANIA, A CORPORATION OF PENNSYLVANIA.

METAL CAR-ROOF.

1,092,484.

Specification of Letters Patent. Patented Apr. 7, 1914.

Application filed January 4, 1912. Serial No. 669,475.

To all whom it may concern:

Be it known that I, JOHN J. HOFFMAN, a citizen of the United States, and a resident of the city of New Kensington, in the county of Westmoreland and State of Pennsylvania, have invented a new and useful Improvement in Metal Car-Roofs, of which the following is a specification.

My invention relates to metal roofs for freight cars, and has for its object the improvement of such roofs to adapt them to withstand the wear and tear of service and to make them watertight.

Further objects of my invention are to strengthen and improve the roof substructure, and to eliminate condensation of moisture on the under surface thereof.

Further my invention will more fully appear in connection with the description of the embodiment thereof illustrated in the accompanying drawings, which are made a part of this specification, and will be pointed out with more particularity in the appended claims.

In the drawings, in which like characters are used to designate like parts wherever they occur throughout the several views,— Figure 1 is a top plan of a portion of a car roof embodying my invention, part of the roof covering being removed to disclose the roof substructure; Fig. 2 is a side elevation of a portion of a car at the eaves, showing my improved roof applied thereto; Fig. 3 is a vertical section on the line 3—3 of Fig. 1

showing a portion of the end of the car in elevation; Fig. 4 is a vertical section on the line 4—4 in Fig. 1; Fig. 5 is a vertical section through the same parts as Fig. 4 but taken at right angles thereto on the line 5—5 in Fig. 4; showing the carline in side elevation; Fig. 6 is a perspective view of the running board saddle bolt locking casting; Fig. 7 is a perspective view of a part of a seam cover showing the hole for the running

board saddle bolt; Fig. 8 is a transverse vertical section through the car at the eaves on the center line of a carline, showing the seam cover hood clip bolts and end of the carline partly in elevation; Fig. 9 is a side elevation of a portion of the car at the eaves showing a seam cover hood clip; Fig. 10 is a transverse vertical section through the car at the eaves on the line 10—10 in Fig. 1 showing

the clip and bolt in elevation; Fig. 11 is a view of the blank for the seam cover hood clip bolt lock; Fig. 12 shows the method of applying the same to secure the seam cover hood clip bolt in the end of the vertical web of the carline; Fig. 13 is a vertical section through the roof at a seam transverse thereto, showing the ends of the purlins and filler blocks in side elevation; Fig. 14 is a top plan view of a portion of a carline showing the method of attachment of the ends of the purlins and filler blocks thereto; Fig. 15 is a top plan view of a portion of the roof adjacent a seam at the point of attachment of a running board saddle, partly broken away to disclose the lining and carline; Fig. 16 is an enlarged vertical section through the roof on the line 16—16 in Fig. 1 showing a running board saddle in elevation; Fig. 17 is a top plan view of the running board saddle and adjacent parts shown in Fig. 16 to the same scale; Fig. 18 is a vertical section on the line 18—18 in Fig. 17; Fig. 19 is a perspective view of the end of a purlin; Fig. 20 is a perspective view of an intermediate running board saddle; Fig. 21 is a perspective view of a meeting running board saddle; Fig. 22 is a diagrammatic view showing a roof sheet in its normal position on the roof; Fig. 23 is a similar diagrammatic view showing the relative arrangement of roof sheet, carlines and side plates with the roof substructure distorted; and Fig. 24 is a perspective view of a roof sheet.

In the drawings, I have illustrated my invention as applied to a car having wooden side and end plates 1, 2 and wood side and end sheathing 3, 4, though it is equally applicable to cars made wholly or partly of metal. In my improved roof the carlines 5 are of commercial T section, bent in the plane of the web 6 to an arc of a circle, and extending from side plate to side plate in parallel vertical arcs with the flanges 7 resting on the side plates and the webs uppermost. The ends 8 of the flanges 7 are bent over the side plates and rigidly bolted thereto. Purlins 9 formed of strips of metal flanged upwardly along the sides to form channels between the points of attachment to the carlines extend longitudinally of the car parallel with the side plates and bridge the spaces between the carlines. These purlins

are rigidly secured to the lateral flanges of the carlines and greatly stiffen the roof substructure from racking and weaving under the varying stresses to which the roof is constantly subjected in service.

Filling pieces 10 of wood are placed in the channels of the purlins and extend from carline to carline, their upper surfaces forming with the side plates the supporting means for the roof sheets 11. Between the purlins are arranged sheathing boards 12, the ends of the sheathing boards resting on the lateral flanges of the carlines. This sheathing, with the fillers in the purlins, forms a complete wood lining under the roof sheets extending from eaves to eaves, and from end to end of the car except for the webs of the carlines projecting through it. The roof sheets are supported above this lining for the most part, thus forming a dead air space divided into isolated sections by the carline webs 6 and filling pieces 10, which air space serves as a heat insulator and also prevents the condensation of moisture on the under side of the roof which is apt to occur to an objectionable extent on metal roofs having no lining.

The roof sheets extend from eaves to eaves and are secured at the eaves by clips 13 attached to the fascias 14 opposite the middle of each sheet by bolts 13^a. These bolts also serve to secure the fascias to the side plates. The sheets are provided with upturned side flanges 15 provided with rebent margins 16 extending inwardly and downwardly.

The ends of the sheets are turned down over the eaves, forming end flanges 17, into rabbets in the tops of the fascias. The sheets, originally rectangular, after flanging are shorter across the middle length than along the side flanges, and the end flanges are deeper at the middle part thereof than at the ends near the corners of the sheets. This widening of the flanges stiffens the ends of the sheet against buckling. The end flanges 17 fit against the inner sides of the rabbets in the fascias at their middle portions, while at the corners of the sheets the flanges are spaced away from the inner sides of the fascias. The clips 13 do not pinch the sheets tightly, but are spaced slightly therefrom to allow some play of the sheet on the substructure. This arrangement prevents the sheets from creeping across the car and overhanging the eaves off one side, and still permits sufficient movement to avoid binding and tearing the sheets. The shape of the ends of the sheets whereby the corners are left plenty of freedom of movement obviates the danger of tearing the sheets when the car is out of square, as is shown diagrammatically in Figs. 22 and 23.

The roof sheets are formed with longitudinal corrugations 18 adjacent to the side mar-

ginal flanges which coöperate with the hollow seam covers 19 to deflect water over the latter and maintain a watertight joint between the sheets. The seam covers extend from eaves to eaves and are approximately inverted U shape, straddling the carlines and sheet side flanges, with their lower margins 35 bent outwardly and flanged to rest on the sheets between the side flanges and corruga-

tions. The tops of the seam covers extend over the tops of the inwardly and downwardly rebent margins of the roof sheet flanges at a distance above them, thus leaving a considerable space over the inturned margins of the roof sheet side flanges within the seam covers. Any water which may splash into this space will run off the slightly downwardly inclined inturned margins of the roof sheet side flanges, and down the inside walls of the seam covers and so off the eaves of the car.

The seam caps are secured at the eaves by hood clips 20 covering their open ends and attached to the ends of the carlines and to the sides of the car by bolts 21, 22. The heads of the bolts attached to the carlines are slipped into slots in the ends of the carline webs, and locked in place by metal strips 23 slipped over the body of the bolt and then bent to embrace the carline web, the projecting sides of the bolt head passing through slots 24 shaped to receive them. The ends of the seam covers, though securely held in place by the hood clips, are free to move longitudinally under the latter with the weaving of the roof substructure.

The seam covers are secured to the tops of the carline web at the middle of the car by the ends 24 of the running board saddles and bolts 26 therefor. These bolts are also secured in notches punched in the webs of the carlines in much the same way as the bolts for the hood clips, except that the bolt locking means 27 is a malleable casting shaped to conform to the under side of the seam covers, and adapted to be passed over the body of the bolt and fitted down snugly on the top of the carline web to form a support for the seam cover as well as a lock for the bolt. This bolt lock and seam cover support is formed with a projection or boss 28 on its upper surface surrounding the bolt hole adapted to fit under similar projections 29 on the seam cover, and the ends 25 of the running board saddles are shaped to conform to the top surface of the seam cover at this point and embrace and cover the latter at the bolt holes, so that when the nuts are tightened to secure the running board saddle and seam cover to the carline no water can find its way between these parts into the car.

Two forms of running board saddles are used, one 30 for the meeting ends of the running boards, and the other 31 to support

the running boards 36 between the meeting ends. The first comprises two side pieces 32 upon which the ends of the running boards are bolted, and a central strap piece 5 33 covering the ends of the running boards and preventing them from warping or splitting and sticking up to trip the brakemen. The intermediate running board saddles comprise a flat strip connecting the two 10 ends, on which strip the running boards rest and to which they are bolted. Both running board saddles are formed with projections 34 extending between the boards to position them and prevent their lateral displacement in case the bolts should not hold 15 securely.

Although the seam covers are rigidly secured upon the carlines of the ridge, and equally well secured at the eaves in so far as 20 any but longitudinal movement thereof is concerned, they are not clamped down on the roof sheets so tightly as to bind the latter and prevent all movement on the sub-structure. Moreover, the sheets are of such 25 dimensions that the side flanges are slightly spaced from the webs of the carlines, and the seam covers are of such width that they straddle the sheet flanges with some space to spare, thus allowing limited freedom of 30 movement of the sheets. The rebent extremities of the sheet flanges and outwardly slanting margins of the sides of the seam covers coöperate to provide a considerable space between the seam covers and sheet 35 flanges for water to collect in and still do not permit much lateral movement of the roof sheets. Some movement of the roof sheets upon the substructure is desirable in order to relieve the sheets of strains due to 40 distortion of the roof substructure under the many and varied stresses of service, but my roof sheet is so formed that this motion need be but slight, and the sheets are so arranged with respect to the other parts of 45 the roof that they will always be maintained substantially in normal position on the roof substructure.

Having described an embodiment of my 50 invention in detail, what I desire to secure by Letters Patent is not limited to the precise forms illustrated and described, but is defined in the following claims based thereon.

I claim:

55 1. A roof sheet for car roofs, said roof sheet comprising a body portion and end flanges and having a greater length from end to end along the side margins of said body portions than along the middle length 60 thereof.

2. A roof sheet for car roofs, said roof sheet having downturned end flanges wider in the middle portion than at the ends thereof, the overall length of said roof sheet

before flanging being the same throughout 65 its width.

3. A roof sheet for car roofs, said roof sheet comprising a body portion varying in length throughout its width, said body portion being shorter along the median line 70 than along the side margins, and flanges of varying width on the ends of said sheet, said flanges being of greater width at the mid portion of the sheet than adjacent the corners thereof.

75 4. In a metal car roof, carlines having vertical webs, purlins between the webs, and roof sheets supported on said purlins, in combination with sheathing supported by said carlines and arranged between said purlins to form dead air spaces beneath the roof sheets.

5. In a car roof, carlines having lateral flanges and vertical webs, purlins attached to said carlines and projecting above said 85 flanges between the webs of the carlines, roof sheets arranged on said purlins between the webs of the carlines, and roof sheathing supported on said carline flanges and spaced below said roof sheets.

90 6. In a car roof, carlines having lateral flanges, purlins attached to said carlines and projecting above said flanges, roof sheets arranged on said purlins, and roof sheathing supported on said carline flanges and 95 spaced below said roof sheets.

7. In a metal car roof, metal roof sheets extending from eaves to eaves in combination with carlines and purlins for supporting the same, and a roof lining supported 100 between said carlines and purlins below said sheets to form isolated dead air spaces beneath the latter.

8. In a metal car roof, carlines having webs provided with dovetail slots, metal 105 cover strips overlying the carlines, supports for the cover strips, said supports being adapted to embrace the carline webs and to conform to the under side of the cover strip, and bolts having heads adapted to be inserted laterally into the slots in the carlines, said supports and cover strips being perforated to pass over said bolts to secure the latter in position in said slots.

9. In a car roof, carlines having webs provided with slots, bolts having heads shaped to conform to said slots and arranged therein, and retaining pieces perforated to receive said bolts and shaped to embrace the said webs to retain said bolts in position.

115 10. In a metal car roof, carlines having webs provided with dovetail slots, metal cover strips overlying the carlines, said cover strips having bolt holes near the ridge, the metal at said bolt holes being formed 120 up, supports for the cover strips, said supports being adapted to embrace the carline webs and to conform to the under side of

- the cover strips at the bolt holes, and bolts having heads adapted to be inserted laterally into the slots in the carlines, said supports and cover strips being slipped over 5 said bolts, and running board saddles shaped to conform to said cover strips at said bolt holes secured by said bolts, said saddles, cover strips and supports forming a water tight structure.
- 10 11. In a car roof, a sheet metal covering therefor, bolt holes in said covering, bolts passing through said holes, bolt retainers arranged below said sheet metal covering at said holes, said bolt retainers being provided 15 with bosses fitting in recesses in the covering surrounding said bolt holes, running board saddles above said covering, the ends of said saddles having holes registering with holes in the covering, said running board 20 saddle ends being formed to engage with projections on said covering surrounding said holes, and means for securing said parts together whereby a water tight structure is maintained.
- 25 12. In a car roof, carlines having webs provided with dovetail slots, bolts with their heads inserted in said slots, metal cover strips slipped over said bolts, said cover strips having bossed bolt holes, supports 30 for the cover strips, said supports embracing the carline webs and the bolts to retain the latter in the dovetail slots, and means cooperating with said bolts for securing said cover strips, said means each having a recess on its under side into which the bossed portion of the cover strip projects to form a water tight joint.
- 35 13. A roof sheet for car roofs, said roof sheet comprising a body portion having inwardly curved ends provided with down-turned end flanges, said end flanges being bowed inwardly toward the center of the sheet.
- 40 14. In a car roof construction, the frame work comprising side plates along the eaves of the car, and a roofing sheet extending from eaves to eaves between and over said side plates and provided with depending end flanges overhanging the outside sides 45 of said side plates, said roofing sheet being loosely secured upon the frame work and having its depending end portions in contact with the side plates at their middle points, said end portions being spaced from 50 said side plates at their ends whereby said roofing sheet is capable of canting in a substantially horizontal plane independently of the side plates.
- 55 15. In car-roof-construction, the frame-work comprising the two laterally spaced side plates, and roofing-sheet extending between and over the side plates and provided at the outer side of each side plate with a depending end-portion, said roofing-sheet 60 being connected to the side plates and mov- able by the side plates during the movement of the side plates occasioned by the weaving or racking of the car and also capable of canting in a substantially horizontal plane independently of the side plates during said movement of the side plates, the depending end-portions of the roofing-sheet having lateral bearing at their inner sides centrally between the side edges of the roofing-sheet and being spaced apart far enough between 65 said bearing and said edges to permit canting of the roofing-sheet.
- 70 16. A roof sheet for car roofs, said roof sheet comprising a body portion provided with down-turned end flanges, said end flanges being bowed inwardly toward the center of the sheet.
- 75 17. A metal car roof comprising a sub-structure and transverse roof sheets supported thereon and arranged at short intervals apart, and hollow seam caps secured at their ends to the substructure and covering the side margins of adjacent sheets, each side of a sheet having its margin bent vertically upwardly and thence inwardly at a small downward inclination, and the hollow seam cap being laterally spaced slightly from the edge of the inturned portion and spaced a greater distance above the upturned portion of said sheet margin.
- 80 18. In a car roof, the combination with side plates of carlines having vertical flanges, roof sheets having vertically upturned side flanges and upward projecting corrugations parallel thereto and spaced therefrom, said side flanges terminating in inturned edges having a slight downward inclination, and seam caps covering the respective carlines and the side flanges of the roof sheets adjacent thereto, each of said 85 seam caps having a lateral flange resting flatwise upon a roof sheet between the corrugation and upturned side flange thereof, and the lower part of the side wall of the seam cap adjacent to said lateral flange being bent outward to provide an enlargement of the space below the inturned edge of the roof sheet within said seam cap.
- 90 19. In a car roof, the combination with side plates, of carlines having vertical flanges, roof sheets having vertically upturned side flanges and upstanding corrugations spaced therefrom, said upturned side flanges terminating in inturned edges inclining downwardly, said roof sheets being arranged between the carlines with spaces between the vertical flanges of the carlines and the side flanges of the roof sheets, seam caps spaced above the side flanges of the roof sheets adjacent to the 95 respective carlines, said seam caps having side walls terminating in lateral flanges resting flatwise upon the roof sheets between the upstanding corrugations and the upturned side flanges thereof, said seam caps 100
- 100 105 110 115 120 125 130

having their side walls spaced slightly from the inturned edges of said roof sheet flanges and the lower parts of the side walls of the seam caps diverging from the roof sheet flanges to provide for an enlarged space below the inturned edges thereof within the seam cap.

Signed at New Kensington, Pa., this 30th day of December, 1911.

JOHN J. HOFFMAN.
